LOCOMOTIVE

James C. Maris, Glenolden, Pa., assignor to The Baldwin Locomotive Works, a corporation of Pennsylvania

Application October 3, 1945, Serial No. 620,125

11 Claims. (Cl. 105—36)

1

This invention relates to locomotives, and particularly to single-cab locomotives of unusual length.

With the present day demand for longer trains, heavier loads and higher speeds, larger and more efficient locomotives present new problems or intensification of old ones, which require solution if safe and economical transportation is to be maintained. These requirements have made longer locomotives a necessity; and this, in time, has introduced new problems due to the stresses and strains set up in the structure of the locomotive because of the great lengths and weights that are involved.

For example, a long heavy locomotive must be raised for services and repairs but the weights and lengths involved make the matter of lifting very difficult as the stresses become focussed on points that cannot always be predisposed to take them and buckling, or failure or parts, becomes a very apparent source of danger.

Some of the objects of this invention are: to provide an improved locomotive assembly in which overhanging weighted parts are so reinforced as to be practically a part of a substantially rigid unitary structure; to provide a steam locomotive with a central boiler section between a power plant section and a fuel bunker section, so related to each that the boiler section may be effectively used in such a manner to add great strength to the unitary structure; to provide a locomotive in which a central steam boiler section has a power plant section connected to it in a simple, direct and sturdy manner; to provide a locomotive wherein increased power is obtained with an efficiency distributed traction, and in which the upper portions of the locomotive are separable for access to the respective portions; to provide a locomotive of maximum length to meet present day load conditions while still capable of negotiating track curves at required speeds, the structure being reinforced to absorb torsion and shear loads arising toward the ends of the locomotives; to provide an elongated locomotive which is reinforced to absorb torsion and shear loads toward the ends of the locomotive while being readily disassembled to enable removal and servicing of the respective end portions of the locomotive; to provide a steam locomotive with a centrally disposed boiler section, and with an end portion carrying the power plant units with reinforcements carrying shear and torsion loads into the central portion and with continuity of the locomotive structure, but which is readily separable for separate and independent relative

movements by cranes for service and repair; and many other objects and advantages which will become apparent as the description proceeds.

In the accompanying drawings, Fig. 1 represents a side elevation of a locomotive embodying one form of the present invention; Fig. 2 represents an enlarged elevation, partially in section, of the power plant assembly at the rear of the locomotive, showing the dismountable tension members of the reinforcing assembly; Fig. 3 represents a transverse section taken on line 3—3 of Fig. 2; Fig. 4 represents a side elevation similar to Fig. 1, with the integrated front and rear end portions disconnected and removed from the central portion in accordance with a feature of the invention; Fig. 5 represents a relatively enlarged side elevation, partially in section, of the removed power plant assembly portion of the locomotive of Fig. 4 as it may be relatively moved from its former position on the locomotive; Fig. 6 represents a view similar to that of Fig. 5, of the front fuel bunker portion of the locomotive assembly as removed from the locomotive of Fig. 4; Fig. 7 represents a transverse section through the locomotive according to the preferred form of invention taken on line 7—7 of Fig. 1; Fig. 8 represents a similar transverse section through the preferred form of locomotive taken on line 8—8 of Fig. 1; and Fig. 9 represents a fragmentary enlarged section of a detail of the tension strut mounting.

Referring to the drawings, a locomotive of the elongated unitary cab type is shown in Fig. 1, wherein the fuel bunker unit 10 is at the front, followed in succession by the engineer's cab portion 11, the boiler and firebox unit in the central portion of the locomotive as shown at 12, and the power generating assembly portion 13 at the rear. The foregoing portions 10, 12 and 13 are referred to herein as locomotive units and these are mounted upon a main frame of the locomotive extending lengthwise beneath all of the units. In the present instance, to facilitate the purposes of the invention, the main frame comprises a front section 14, a rear section 15, and an intermediate section 16, which latter serves to support the main load, and includes saddles 17 upon which the boiler 18 is seated. The two pairs of meeting ends, respectively of 15 and 16, and of 14 and 16, are arranged for interfitting and interlocking relation in any desired manner to enable dismounting when required, but to maintain rigid coextension of the respective main frame portions in anchored assembly during the operative condition of the locomotive. As illustrated, the rear sill

2

or frame portion 15 at its front end and the front sill or frame portion 14 at its rear end are stepped to provide a downwardly presenting horizontal step surface 19 between staggered vertical wall surfaces 20 and 20¹ forming an underhanging end. Both ends of the central frame portion 16 are shaped complementally thereto. Each end has an upwardly presenting horizontal surface 21 between staggered vertical walls 22 and 23, reversely staggered relative to vertical surfaces 20 and 20¹ of the frame sections 14 and 15 and forming an overhanging end. The parts are juxtaposed with the respective horizontal and vertical surfaces in contact and are anchored in this relation. An illustrative form of anchor comprises an upper flanged slotted or angular U-shaped strap 24, or a plurality thereof, engaging lips 25 and 26 on the respective sections, and bolted to the sections through the flanges as by bolts 31. A lower flanged slotted or angular U-shaped strap 27 or plurality thereof engages lips 28 and 30 on the respective sections, and bolts or the like 31 fasten the lower straps to the sections. It will be understood that similar end, but reversed, formations and fastenings are provided for the juncture of the central section 16 with the front section 14. It will be observed that the terminal extensions will be for all practical purposes rigid continuations of the main central frame section 16, being braced and held against both torsion and shear at the joints. The front end of section 16 will be shaped similarly to the rear end but presenting an underhanging end in the opposite direction.

For supporting the sectional main frame of the locomotive with its supported parts, to be described, a plurality of trucks are provided including a front guiding truck 33, a power driven truck 34, an intermediate truck 35, a rear power driven truck 36, and a trailer truck 37. Thus, the fuel bunker section 14 is carried by a center pivot bearing 38 upon the power truck 34, while the forward extension of the latter is carried by the bolster 40 of the guiding truck 33. The boiler unit 12 and the generator unit assembly 13 are supported by a center pivot bearing 41 between the main frame portion 16 and the power driven truck 36, the opposite end extensions of the latter being supported respectively by the bolster 42 of the intermediate truck 35, and the trailer truck 37.

The front end of the locomotive comprising the fuel bunker 10 is covered by a housing or hood 43, suitably apertured to receive fuel, and carries the intake end 44 of the stoker device 45, and the stoker is arranged for disassembly or separation at a point 46 under the cab portion 11 of the locomotive. The fuel section 10 is braced by sets of respectively laterally disposed inclined struts 47, 48, and 50, extending between the main frame front extension 14 and the smaller sub-frame member extending longitudinally of the fuel section 10, as at 51, and terminating in an eye piece 52 mounted on a vertical compression strut 53 extending between the eye piece and sub-frame 51, and the frame section 14 adjacent to the rear end of the latter. When the front section is to be tied in to the main section of the locomotive, an inclined tension member 54 is connected at the upper end to the eye piece 52, and at its lower rearward end to an eye stud 55 mounted rigidly on the main central frame section 16 adjacent to the forward end of that section. The hood 43 of the fuel section is abutted in a line of jointure 75

with the unitary housing 75 of the cab and steam boiler portion so that the jointure is in a plane transverse of the locomotive. If desired, this joint can be sealed in any desired way, but it is important that the housings be readily separable, so that upon disconnecting the stoker at 46, removing the tension links 54 from each side of the locomotive, and disconnecting the abutting ends of the sections 16 and 14, by removing the anchoring straps, the entire fuel section end can be lifted by a crane and removed for any desired purpose without disrupting any portion of the remainder of the locomotive. This is indicated in a general way by the relationship of the fuel section 10 of Fig. 6, to the partially dismantled locomotive in Fig. 4.

The rear end of the locomotive contains, in portion 13, the power plant of the locomotive, namely the steam turbine and generators for the electric motors associated with the power wheels of the trucks, one form of suitable motorized trucks being disclosed in my copending application, Serial No. 623,323, filed October 19, 1945. Obviously, any sort of conversion system can be used, but, illustratively, generators 57 are driven by turbine 58, and these are mounted on the sill or main frame rear extension section 15. These units are very heavy and may not rely safely for their sole support upon the rigidity of the anchorage of the extension frame to the main sill or frame section 16, especially in view of the inevitable upward and downward impulses and the swaying or yawing impulses developing as a function of the deviations of the locomotive from straight smooth travel. The bending moments thus developed would be severe.

To reinforce the rear power plant assembly portion, a pair of laterally disposed side sub-frame members are provided as at 60 a little over half way up from the sill portion 15 to the upper limits of the housing structure 61 of the rear portion 13, and extending longitudinally of the portion substantially parallel to frame 15, and a plurality of inclined truss members respectively 62, 63, 64 and 65 extend rigidly between the main frame member 15 and the sub-frame members 60, to make rigid the whole. Each sub-frame member 60 includes a rearwardly disposed thrust block 66 having a bore 67 through which a tension rod 68 passes from an anchor tie 70 on the upper portion of the end of the boiler 18, from which the tension rod is disconnectible when desired. The lower free end of the tension rod 68 beyond the thrust block 66 carries a flanged element 69 against which a pair of concentric coiled springs, respectively 71 and 72 surrounding the rod 68 are compressed between element 69 and the thrust block 66. It will be seen that the loaded springs 71 and 72 give a little relief to permit slight flexure of the extreme end of the rear unit 13 in response to exaggerated "whipping" thereof. For all normal locomotive use, even at high speeds, however, the tension on the rod 68 and the loading of the springs is such that little relative motion of the rod end 68 and the block 66 occurs. At the forward or boiler end each of the respective sub-frame members 60 carries an eye 73 just inside of the front edge 74 of the housing 61 of the rear unit, where it abuts the complementary edge of the housing 75 of the central boiler unit. A tension rod 76 is removably connected to the eye 73 and extends forwardly and downwardly to an eye 71 anchored rigidly to the main frame section 16, at an appreciable

distance from the rear end of the frame section. The tension rods 68 and 76 carry the excess loads of the rear portion into the central boiler section, as will be clear. It will also be clear that it is merely necessary to uncouple the tension rods, at one or the other or both ends thereof, and to remove the flanged clamping pieces from the joint between the main frame portions 15 and 16, with any other connections that may have been established between the portions, when it will be possible to disconnect and remove the entire power plant assembly 13. Such removal enables work upon and service to the rear portion alone, or the replacement thereof with another assembled unit during the repairs, as well as work upon the adjacent portions of the central portion, with ease and quickness.

It is thought that the simplicity and advantages of the invention will be clear.

Having thus described my invention, I claim:

1. A locomotive comprising a plurality of power trucks, and a main frame pivotally supported on each of said power trucks, said main frame comprising a plurality of sections, means for detachably uniting the sections together so that said main frame is a single continuous rigid structure, a locomotive superstructure comprising a plurality of units respectively mounted on and removable with the respective sections of the main frame, and supplemental detachable means for connecting the respective units together and for assisting the first mentioned means in transmitting the load of one unit to the adjacent unit.

2. A locomotive comprising a main frame section, a steam boiler section mounted on the main frame section, a power plant unit including a main frame supplemental extension, truss means in the power plant unit having an attaching point above the level of the main frame section, and means for detachably connecting the steam boiler section to the attaching point of the truss means of the power plant unit to transmit stresses arising in the power plant unit to the steam boiler unit whereby substantially the entire weight of said power plant is carried by said main frame section.

3. A locomotive comprising a plurality of power trucks, a steam boiler plant unit and a power plant unit in longitudinally juxtaposed relation, means coupling the power plant unit to and substantially supporting it on the steam boiler plant unit in a rigid locomotive assembly, said means being detachable to permit separation of the power plant unit from the locomotive, and means for pivotally supporting the rigid locomotive assembly on each of said trucks.

4. A locomotive comprising a steam boiler plant unit and a power plant unit in longitudinally juxtaposed relation the boiler plant unit including a main frame section and the power plant unit including a longitudinally juxtaposed main frame section, means for supporting the power plant frame section on the boiler plant frame section, means for coupling the power plant unit to the steam boiler plant unit, and means for detachably connecting said frame sections together whereby upon disconnection of the coupling means and the detachable means the power plant unit, together with its frame section can be removed as a unit from the steam boiler plant unit.

5. A locomotive comprising a main frame composed of a plurality of longitudinally aligned

frame sections including a main section and an extension section, means detachably connecting the sections into a substantially rigid main frame, an articulated wheeled truck system for the main frame, plural means disposed between the main section and the truck system in longitudinally spaced relation for transmitting the loads of the main section to the truck system, a locomotive superstructure mounted on the substantially rigid main frame and including a substantially continuous housing having a plurality of transverse surface breaks, said breaks defining on each side longitudinally of the locomotive related but separate locomotive units, means separate from the housing for detachably connecting adjacent units together to carry supporting stresses from the unit mounted on the extension section into the adjacent unit mounted on said main section whereby upon detachment 20 of the frame section connecting means one such unit and its frame section and housing can be bodily removed from the remainder of the locomotive including said wheeled truck system.

6. A locomotive comprising a main frame 25 formed of a plurality of relatively aligned sections, means for detachably connecting the juxtaposed ends of adjacent sections to each other, a power plant unit mounted on one frame section, bracing truss means operatively connected 30 to the power plant frame, a locomotive unit mounted on the main frame section adjacent to the power plant unit, means for detachably connecting the bracing truss means to a portion of the said locomotive unit above the level of the said 35 main frame section thereof to transmit stresses arising in the power plant unit into the said locomotive unit, said bracing truss means being provided on each side laterally of the power plant unit, and said last mentioned detachable connecting means comprising tension means having a point of attachment to said locomotive unit higher than its attachment to the bracing truss means.

7. A locomotive comprising a main frame 45 formed of a plurality of relatively aligned sections, means for detachably connecting the juxtaposed ends of adjacent sections, a power plant unit mounted on one frame section, bracing truss means including a frame element spaced from 50 the main frame section, a locomotive unit mounted on the main frame section adjacent to the section mounting the power plant unit, means for detachably connecting the frame element of the bracing truss means to a portion 55 of the said locomotive unit above the level of the said main frame section thereof to transmit stresses arising in the power plant unit into the said locomotive unit, said bracing truss means being provided on each side laterally of the power plant unit, and said last mentioned means for detachable connection comprising tension means having a point of attachment to said locomotive unit higher than its attachment to the bracing truss means, and supplemental tension means extending from said frame element 60 to the main frame section of said locomotive unit.

8. A locomotive comprising a main frame 70 formed of a plurality of relatively aligned sections, means for detachably connecting the juxtaposed ends of adjacent sections in substantially rigid relation, a locomotive unit mounted on each of adjacent sections of the main frame, a truss bracing on one locomotive unit connected to its main frame section and having a thrust block

above the level of the said main frame section thereof, a tension rod extended through the thrust block and connected detachably to the adjacent locomotive unit, said tension rod having a transverse abutment, and a loaded coil spring surrounding the tension rod engaged between the abutment and the thrust block and arranged to yield and expand in response to variations in torsional stresses arising in the first mentioned locomotive unit relative to the detachable connection between the main frame sections of the said respective juxtaposed locomotive units.

9. A locomotive comprising a main frame formed of a plurality of relatively aligned sections, means for detachably connecting the juxtaposed ends of adjacent sections in substantially rigid relation, a plurality of locomotive units mounted respectively on each of the respective main frame sections, longitudinally extending detachable connections between adjacent locomotive units to form a complete integrated unitary locomotive, said means for detachably connecting and said detachable connections being arranged for disconnection to permit removal of one locomotive unit relative to an adjacent unit, said respective locomotive units comprising a central steam boiler unit, and terminal power plant and fuel tender units.

10. A locomotive comprising a main frame formed of a plurality of relatively aligned sections, means for detachably connecting the juxtaposed ends of adjacent sections in substantially rigid relation, a plurality of locomotive units mounted respectively on each of the respective main frame sections, longitudinally extending detachable connections between adjacent locomotive units to form a complete integrated unitary locomotive, said means for detachably connecting and said detachable connections being arranged for disconnection to permit removal of one locomotive unit relative to an adjacent unit, said respective locomotive units comprising a central steam boiler unit, terminal power plant and fuel bunker units, and each said unit having an enclosing housing,

with the respective housings in substantial abutting engagement to form a unitary single housing for the entire locomotive in assembly.

11. A locomotive comprising a main frame formed of a plurality of relatively aligned sections, means for detachably connecting the juxtaposed ends of adjacent sections in substantially rigid relation, a plurality of locomotive units mounted respectively on each of the respective main frame sections, longitudinally extending detachable connections between adjacent locomotive units to form a complete integrated unitary locomotive, said means for detachably connecting said detachable connections being arranged for disconnection to permit removal of one locomotive unit relative to an adjacent unit, truss bracing on at least one of the locomotive units including a frame member spaced from the main frame section of the instant unit, said truss bracing including a longitudinally spaced thrust block and an eye piece, said detachable means comprising a tension rod engaging the thrust block and extending to the adjacent locomotive unit above the level of the main frame section thereof, and a tension device engaging the eye piece and connected to the main frame section of said adjacent locomotive unit.
